UNITED STATES PATENT OFFICE

134,192

DESIGN FOR A SHOE

Mabel Julianelli and Charles A. Julianelli,
New York, N. Y.

Application September 9, 1942, Serial No. 108,162

Term of patent 3½ years

To all whom it may concern:

Be it known that we, Mabel Julianelli and Charles A. Julianelli, both citizens of the United States of America, residing in the city, county, and State of New York, have invented a new, original, and ornamental Design for a Shoe, of which the following is a specification, reference being had to the accompanying drawing, forming part thereof. The figure on the drawing is a front perspective view of a shoe showing our new design. The opposite side presents substantially the same appearance as the side shown.

We claim:

The ornamental design for a shoe, substantially as shown and described.

MABEL JULIANELLI.
CHARLES A. JULIANELLI.
